(57) **CLAIM**

The ornamental design for a combination light and ceiling fan, as shown and described.

DESCRIPTION

FIG. 1 is a bottom perspective view of a combination light and ceiling fan from below showing our new design in the “ON” state;

FIG. 2 is a top perspective view from above our ceiling fan in the “ON” state;

FIG. 3 is a side elevation view of our ceiling fan in the “ON” state, all sides being mirror images of each other;

FIG. 4 is a top plan view of our ceiling fan in the “ON” state;

FIG. 5 is a bottom perspective view from our ceiling fan in the “OFF” state;

FIG. 6 is a top perspective view from above our ceiling fan in the “OFF” state;

FIG. 7 is a side elevation view of our ceiling fan in the “OFF” state, all sides being mirror images of each other; and

FIG. 8 is a top plan view of our ceiling fan in the “OFF” state.

FIG. 9 is a second embodiment of a bottom perspective view of a combination light and ceiling fan from below showing our new design in the “ON” state;

FIG. 10 is a top perspective view of FIG. 9 from above our ceiling fan in the “ON” state;

FIG. 11 is a side elevation view of FIG. 9 of our ceiling fan in the “ON” state, all sides being mirror images of each other;

FIG. 12 is a top plan view of our ceiling fan of FIG. 9 in the “ON” state;

FIG. 13 is a bottom perspective view from our ceiling fan of FIG. 9 in the “OFF” state;

FIG. 14 is a top perspective view from above our ceiling fan of FIG. 9 in the “OFF” state;

FIG. 15 is a side elevation view of our ceiling fan of FIG. 9 in the “OFF” state, all sides being mirror images of each other; and,

FIG. 16 is a top plan view of our ceiling fan in FIG. 9 in the “OFF” state.

The broken lines are for illustrative purposes only and form no part of the claimed design.
